UNITED STATES PATENT OFFICE.

EPHA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

SHUTTLE PLACER FOR WEFT-REPLENISHING LOOMS.

Application filed August 8, 1922. Serial No. 580,526.

This invention relates to automatic weft replenishing looms of the type in which a fresh weft carrier is inserted upon substantial exhaustion of weft in the active shuttle. 5 More specifically, my invention relates to devices for cutting the trailing weft ends at the selvage after weft carrier transfer, in combination with devices for positioning the shuttle in the shuttle box at the time of 10 transfer.

One object of my invention is to provide an improved and simplified structure for a combined thread cutter and shuttle placer. Another object is to provide connections 15 through which these devices may act to revoke the transfer in the event of a widely misplaced shuttle.

My invention further relates to arrangements and combinations of parts which will 20 be hereinafter described and more particularly pointed out in the appended claims.

A preferred form of the invention is shown in the drawings, in which

Fig. 1 is a side elevation of parts of a weft 25 carrier magazine with my invention mounted thereon;

Fig. 2 is a front elevation of my improved thread cutter and shuttle placer;

Fig. 3 is a sectional plan view taken along 30 the line 3-3 in Fig. 1; and

Fig. 4 is a detail view looking in the direction of the arrow 4 in Fig. 1.

Referring to the drawings, I have shown parts of a magazine frame 10 of the usual 35 type supported upon the loom frame 11. A shuttle S and a portion of the lay 12 are also shown in the drawings.

My improved thread cutter comprises a 40 depending arm 13 mounted on a fixed pivot in a bracket 14 secured to the magazine 10. A lever 15 is pivoted at 16 to the arm 13 and is yieldingly held in the position shown in Fig. 1 by a coil spring 17 mounted between the arm 13 and the upper end 18 of the 45 lever 15. A rearwardly projecting portion 19 of the arm 13 is yieldingly connected by a link 20 to an arm 21 upon a cross shaft 22 mounted in fixed bearings in the magazine frame 10.

Thread clamping plates 23 and 24 are provided at the lower end of the lever 15, the plate 24 being yieldingly pressed downward by a spring 25 and the plate 23 being pivoted at 27 to the lever 15. A thread cutting 50 plate 26, indicated in dotted lines in Fig. 1,

is also pivoted at 27 on the lever 15. The plate 23 and cutter 26 are actuated by a link 28 which is yieldingly slideable through a sleeve 29 mounted on a fixed pivot 30 on the bracket 14. The parts are swung downward 60 or opened as the arm 13 and lever 15 are swung rearward to meet the lay and shuttle.

A shuttle engaging roll or placer 32 is rotatably mounted on a bearing 33 projecting from the side of the lever 15 and is adapted 65 to engage the point of a slightly misplaced shuttle and to force the shuttle into the shuttle box as the lay advances. The shaft 22 is actuated by a selected sliding bar 31 to move the thread cutter and roll rearward to 70 meet the lay upon indication of transfer, the mechanism for producing such movement being fully described in my prior Patent No. 1,030,748, issued June 25, 1912. The parts are held yieldingly in this rearward 75 position by the spring toggle members 34 and 35 shown in Fig. 4.

The toggle member 35 includes a block 36 engaged by a spring 37 and designed to hold the toggle firmly although yieldingly against 80 displacement in both of its two positions.

The member 35 is connected to an arm 36' from which a link 37a extends to a latch, not shown, by which the transference is actuated.

Under normal running conditions, the 85 parts are in the position shown in Fig. 1, in which the shuttle placer or roll 32 will engage the shuttle as the loom approaches front center. If the shuttle is widely misplaced, the link 20 will yield to permit the 90 placer to be swung forward and thus prevent breakage of parts.

Upon indication of transfer, the thread cutter and placer are swung rearward to 95 grasp and cut the thread at an earlier point in the forward movement of the lay, simultaneously boxing the shuttle.

If the shuttle is so widely misplaced that the cam-like action of the roll 32 is not sufficient to move the shuttle to correct position, 100 the shuttle placer and thread cutter will be swung forward as previously described, at the same time lowering the link 37 and its associated latch out of the path of the bunter or actuating device carried by the lay. My 105 improved shuttle placer thus acts to revoke the transfer when engaged by a widely misplaced shuttle. If the transfer is not revoked, the parts will be thereafter returned to their normal or reset position by the 110

usual operation of the transfer mechanism.

From this description, it will be seen that I have provided a very simple combined thread cutter and shuttle placer which is normally in forward position and which is moved rearward to render the cutter operative only upon indication of transfer.

Furthermore, I have provided such a structure which also acts to revoke the transfer when engaged by a widely misplaced shuttle. The parts are of simple construction and move in a single plane about a fixed pivot, distinguishing my invention in this respect from the structure shown in the prior patent to McGuinness No. 1,261,417, issued April 2, 1918.

Having thus described my invention, I do not wish to be limited to the details herein disclosed otherwise than as set forth in the claims, but what I claim is:—

1. In a loom having a weft carrier magazine, a lay and a shuttle, in combination a depending supporting member mounted on a pivot on said magazine and swinging 25 downward in the path of the advancing shuttle, said member having movement in a single plane only and substantially perpendicular to the path of the shuttle, a shuttle positioning roll mounted on said member to rotate about a substantially vertical axis 30 when in operative position, said member and roll having a normal forward inoperative position, and means to move said parts rearward upon indication of weft carrier transfer to position said roll for engagement by a misplaced shuttle.

2. In a loom having a weft carrier magazine, a lay and a shuttle, in combination a

depending supporting member mounted on a pivot on said magazine and swinging 40 downward in the path of the advancing shuttle, said member having movement in a single plane only and substantially perpendicular to the path of the shuttle, a shuttle positioning roll mounted on said member to 45 rotate about a substantially vertical axis when in operative position, said member and roll having a normal forward inoperative position, and means to move said parts rearward upon indication of weft carrier transfer to position said roll for engagement by a misplaced shuttle, said parts being effective 50 to revoke the transfer when engaged by a widely misplaced shuttle.

3. In a loom having a weft carrier magazine, a lay and a shuttle, in combination a depending supporting member mounted on a pivot on said magazine and swinging 55 downward in the path of the advancing shuttle, said member having movement in a single plane only and substantially perpendicular to the path of the shuttle, a shuttle positioning roll mounted on said member to rotate about a substantially vertical axis 60 when in operative position, said member and roll having a normal forward inoperative position, and means to move said parts rearward upon indication of weft carrier transfer to position said roll for engagement by a misplaced shuttle, said parts being effective 65 to position the shuttle engaged thereby as the lay moves forward and before weft carrier transfer takes place.

In testimony whereof I have hereunto affixed my signature.

EPPA H. RYON.
